Primary Examiner — Elizabeth J Oswecki(74) *Attorney, Agent, or Firm* — Fitch, Even, Tabin and Flannery LLP(57) **CLAIM**

We claim the ornamental design for a adapter plate, as shown and described.

DESCRIPTION

FIG. 1 is a front, top and right side perspective view of an adapter plate showing our new design;

FIG. 2 is a front elevational view thereof;

FIG. 3 is a rear elevational view thereof;

FIG. 4 is a top plan view thereof;

FIG. 5 is a bottom plan view thereof; and

FIG. 6 is a left side elevational view thereof;

FIG. 7 is a right side elevational view thereof; and,

FIG. 8 is a cross-sectional view taken along lines **8-8** in FIG. 2.**1 Claim, 4 Drawing Sheets**FIG. 1

FIG. 2

FIG. 3

FIG. 4

FIG. 5

FIG. 6

FIG. 7

FIG. 8
